ATTORNEY

UNITED STATES PATENT OFFICE.

CLAUDE T. V. HANSEN, OF McMINTNVILLE, OREGON.

GUN-CLEANER.

1,256,478.

Specification of Letters Patent. Patented Feb. 12, 1918.

Application filed March 3, 1917. Serial No. 152,325.

To all whom it may concern:

Be it known that I, CLAUDE T. V. HANSEN, a citizen of the United States, residing at McMinnville, in the county of Yamhill and 5 State of Oregon, have invented new and useful Improvements in Gun-Cleaners, of which the following is a specification.

This invention relates to gun cleaners, which are commonly called ramrods. 10 The object of the invention is to provide a rod by means of which the bores of shot guns or rifles may be easily cleaned with a minimum amount of time and labor.

Another object is to provide means which 15 will positively prevent accidental leaving of the cleaning cloth within the barrel of the gun and will distribute the said cloth evenly within the bore and prevent the bunching thereof, which results in great annoyance 20 and an imperfect cleaning of the gun.

With these and other objects in view the invention consists of the following novel combination and arrangement of parts which will be hereinafter more fully 25 described, illustrated in the accompanying drawings and pointed out in the appended claim.

In the drawings;

Figure 1 is a view of a ramrod for use in 30 cleaning guns constructed in accordance with the present invention;

Fig. 2 is an enlarged perspective view of the removable section;

Fig. 3 is a view of a modified form of 35 removable section, having a portion of the rod shown connected thereto, this rod being of the same diameter as the point carrying portion of the section for the purpose of reducing the weight of the rod; and

Fig. 4 is a view of a further modified 40 form illustrating the removable section as split.

In the embodiment of the invention illustrated in Fig. 1, there is provided a rod 10 45 preferably the size for convenient use within the bore of the gun to be cleaned, the said rod being provided with any suitable handle or hand grip 11 for convenience in use. The opposite end of the rod is formed with a 50 threaded bore 12 and within this bore is adapted to be received the reduced threaded end 13 of the removable section 14. The section 14 is of lesser diameter than the rod 10, and the rod is beveled as at 15 so as to elimi-

nate the sharp point or shoulder at this 55 point.

The section 14 is formed or provided with angularly disposed engaging points 16, these points terminating within the diameter of the rod 10. The points 16 are arranged 60 in rows as shown, each alternate row being disposed at an opposite angle, so that when the cloth is in position thereon and inserted within the bore of the gun independent movement of the said cloth will be prevented 65 in either direction, thereby, positively holding the cloth in position upon the rod and preventing bunching or accidental removal from the rod. If desired the section 14 may be made hollow for the purpose of reducing 70 the weight of the same when constructed for guns of large gage or caliber.

In Fig. 3 the diameter of the section 14 and rod 10 is the same and in order to prevent contact of the points 16 with the bore 75 of the gun the section 14 is provided with a collar 17. In this form the engaging points terminate within the diameter of this collar.

In Fig. 4 there is a still further modification of the invention, in which the section 80 14^a is split as shown at 18 and as the section is formed of spring metal the cloth thereon will be more positively engaged through the points 16.

Where it is desired to provide rods for 85 guns of small caliber the section 14 or 14^a may be constructed integral with the rod 10.

It is believed that from the foregoing description the operation and advantages of the invention will be apparent and that a 90 further description is unnecessary.

Having described the invention, what is claimed is;

A gun cleaner comprising in combination a rod having a threaded socket in one end 95 thereof, a tip of relatively smaller diameter within said rod, one end of the tip being reduced and threaded for engagement with the threaded bore of the rod and longitudinal rows of engaging points extending at an 100 angle from the tip, the inclination of each alternate row being oppositely disposed in a direction parallel with the length of the rod, the said points terminating within the diameter of the rod. 105

In testimony whereof I affix my signature.

CLAUDE T. V. HANSEN.
